(57) **CLAIM**

The ornamental design for an automatic tablet packing
machine, as shown and described.

DESCRIPTION

FIG. 1 is a front view of automatic tablet packing machine;
FIG. 2 is a rear view thereof;
FIG. 3 is a top view thereof;
FIG. 4 is a bottom view thereof;
FIG. 5 is a right-side view thereof;
FIG. 6 is a left-side view thereof;
FIG. 7 is a perspective view looking from the upper right-side
direction of automatic tablet packing machine; and,
FIG. 8 is a perspective view showing the automatic tablet
packing machine in an alternate condition of use with the door
opened and a tablet case pulled out.
The broken lines in the drawings depict unclaimed environmental
subject matter.

UNITED STATES PATENT AND TRADEMARK OFFICE
CERTIFICATE OF CORRECTION

PATENT NO. : D643,865 S
APPLICATION NO. : 29/386923
DATED : August 23, 2011
INVENTOR(S) : Yasutoshi Okamoto et al.

Page 1 of 1

It is certified that error appears in the above-identified patent and that said Letters Patent is hereby corrected as shown below:

Title Page (75) Inventors, reads as follows:

“Yasutoshi Okamoto, Moriguchi (JP);
Fumio Yamada, Moriguchi (JP);
Akihiro Mochizuki, Moriguchi (JP)”;

should read:

--Yasutoshi Okamoto, Moriguchi-city, Osaka (JP);
Fumio Yamada, Moriguchi-city, Osaka (JP);
Akihiro Mochizuki, Moriguchi-city, Osaka (JP)--;

and

Title Page, (57) Claim, line 1, delete the word “an”.

Signed and Sealed this
Fourteenth Day of August, 2012

David J. Kappos
Director of the United States Patent and Trademark Office
